(57) CLAIM

The ornamental design for a semiconductor element, as shown and described.

DESCRIPTION

FIG. 1 is a top, front perspective view of a semiconductor element showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and

FIG. 7 is a front elevational view of another embodiment of a semiconductor element, which is transparent, showing our new design;

FIG. 8 is a rear elevational view thereof;

FIG. 9 is a right side elevational view thereof;

FIG. 10 is a left side elevational view thereof; and,

FIG. 11 is a top plan view thereof, a bottom plan view thereof being a mirror image.

Portions in broken lines are for illustrative purposes only and form no part of claimed design.
